CLAIM

The ornamental design for a showerhead as shown and described.

DESCRIPTION

FIG. 1 is a perspective view of a showerhead, showing our new design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

Broken lines illustrate portions of the showerhead that form no part of the claimed design.
